CIGARETTE EXTINGUISHER

Sperling Carlson, 915 22nd Ave. W., Duluth, Minn.
Filed Sept. 5, 1962, Ser. No. 221,562
6 Claims. (Cl. 131—237)

This invention relates to a new and improved means for snuffing out the burning ashes of cigarettes, cigars and the like; in particular, the invention is concerned with a novel combination, suited for either mounting on an ash tray or for use by itself, adapted to apply positive mechanical means to snuff out and squeeze the burning end of a cigarette, cigar or the like.

Many cigarette extinguishers and snuffers employ structure adapted to facilitate the hand snuffing and/or extinguishing of a cigarette. These types typically include a conical shaped body having a lower opening of less diameter than a cigarette. By forcing a cigarette into the upper end of the structure the lower burning end is wedged into contact with the side walls of the extinguisher. By constructing the device of thin heat conducting material, the heat from the burning end of the cigarette is dissipated through its contact with the lower end of the cone-shaped body. In theory, the resulting cooling action extinguishes the cigarette by thermal conduction; however, such devices are not always certain of accomplishing their desired results particularly if the zone of contact becomes coated with tar, ash, or other foreign matter that may form an insulating barrier and prevent efficient thermal conduction of the heat generated by the burning end of the cigarette. To overcome this reliance upon extinguishing by cooling action alone or by the alternative method of manually snuffing out the end of a cigarette by axial force, I have devised a combination adapted to apply positive mechanical forces to the cigarette with a minimum of effort.

It is a broad object of this invention to provide an improved cigarette extinguisher.

Another important object of this invention is to provide a cigarette extinguisher that relies upon unique mechanical means for completely and positively eliminating the burning members of a cigarette.

Yet another object of this invention is to provide in a cigarette extinguisher, novel means for initially squeezing the end of a cigarette and subjecting the end of a cigarette to a wiping action whereby to positively remove any possibility of a latent afterburning of the ash.

A further object of this invention is to provide in a cigarette extinguisher novel means for cushioning the parts employed for squeezing and wiping the end of a cigarette.

Another object of this invention is to provide in a cigarette extinguisher novel means for supporting and guiding the cigarette during the extinguishing procedure.

Another object of this invention is to provide a cigarette extinguisher that may be easily manufactured of readily available parts, is relatively low in cost, highly efficient in operation, and rugged in design.

A further object of this invention is to provide a cigarette extinguisher adapted for mounting on ash trays of widely varying types or adapted for portable use.

Another object of this invention is to provide in a cigarette extinguisher novel linkages adapted for easy hand manipulation to effect a combined squeezing and wiping action against the burning end of a cigarette.

These and other objects and advantages of the invention will become more fully apparent from a consideration of the following detailed description and accompanying drawings wherein an embodiment of the invention is shown for purposes of illustration and not by way of limitation.

2

In the drawings:

FIGURE 1 is a perspective view illustrating the invention mounted upon an ash tray;

5 FIGURE 2 is a rear elevation view of the invention;

FIGURE 3 is a front elevation view of the invention;

FIGURE 4 is a top view of the invention;

10 FIGURE 5 is a side view of the invention with a portion of the ash tray upon which it is mounted being shown in dotted lines;

15 FIGURE 6 is a side elevational view of the extinguisher and a part of the ash tray shown in FIG. 1 with a side wall broken away, the end walls and the ash tray therebelow being shown in section;

FIGURE 7 is a view similar to FIGURE 6 showing the side opposite to that illustrated in FIGURE 6;

20 FIGURE 8 is a view similar to FIGURE 6 illustrating the final step in the coaction of the pressure plate and the anvil member;

FIGURE 9 is a view similar to FIGURE 6 illustrating the intermediate coaction of the pressure plate and the anvil member;

25 FIGURE 10 is an enlarged fragmentary view, partially in section, taken substantially along the line 10—10 of FIGURE 1, illustrating the initial coaction of the pressure plate and the anvil member;

FIGURE 11 is a perspective view of the middle yoke member forming part of the invention;

30 FIGURE 12 is a perspective view of the lower yoke member forming part of the invention; and

FIGURE 13 is a perspective view of the upper yoke means forming part of the invention.

Referring now to the drawings, the invention, indicated 35 in its entirety by the reference character A, is shown in FIGURE 1 as being mounted upon an ash tray 20. It is, of course, possible to use the invention separate from an ash tray, for example, it may be carried about as a portable extinguisher in the same manner as a cigarette lighter. The invention includes an outer body 22 having generally closed side walls 24, a rear end wall 26, a forwardly inclined front wall 28 and a sloping top 30. A flat thin bracket 32 may be attached to the lower rear of body 22 to permit the pivotal mounting of the invention 40 upon the lip 21 of an ash tray or similar article, as indicated at 34.

45 As illustrated in FIGURES 6-10, inclusive, a rigid elongated generally flat support bar 40 is mounted within body 22 between walls 24 in a downwardly and forwardly inclined manner generally parallel to the slope of front wall 28. Support bar 40 extends beyond the lower edges of body 22 and in contact with the recessed bottom 23 of ash tray 20. Surroundingly secured to the upper half of support bar 40 is an anvil member 42. Anvil member 42 consists of a thin hard outer shell 44 that is inclined 50 slightly with respect to the vertical, as at 46. Between the forward surface of support bar 40 and shell 44 is contained a layer 46 of resilient material, such as sponge rubber or its equivalent, having a wedge shape complementary to the shape of outer shell 44. Also carried within shell 44 is a slender hook-like spring member 48 positioned between layer 46 and outer shell 44 and having an upper end 50 protruding through an aperture 52 in shell 44 in a direction normal thereto.

55 Pivots secured to the upper end of support bar 40, at 41, is an upper yoke member 60 having a pair of spaced forward arms 62 surrounding anvil member 42 and a rear cross bar 64 extending downwardly and forwardly therefrom. The free end of upper yoke member 60 is equipped with a finger engageable cross bar 66 60 while the lower rear part of the arms 62 are provided with a pair of apertured lugs 68. A lower yoke member 70

is pivotally attached to support bar 40 below anvil member 40. Yoke member 70 has a pair of spaced forward arms 72 and an upstanding rear cross bar 74. Arms 72 are equipped with a pair of forward apertures 74' and a pair of intermediate apertures 76. Connection between yoke member 70 and support bar 40 is made by a pin 77 which mounts through apertures 76 of yoke member 70 and a corresponding aperture in support bar 40. The forward apertures 74' of yoke member 70 permit a pinned pivotal connection between the lower end of an elongated flat pressure plate 80 and the forward end of yoke member 70. Pressure plate 80 is further pivotally connected intermediate its lower end and its center with the forward arms 92 of a middle yoke member 90. The arms 92 of middle yoke member 90 have a pair of upstanding apertured lugs 96 suited for a pinned pivotal connection, as at 98, with the lower lugs 68 of upper yoke member 60. As indicated generally in FIGS. 1-5, the pivots 41 and 77 extend through the members 24 and serve additionally to position the support member 40 with respect to the outer body 22.

Means for urging pressure plate 80 in an outward direction away from anvil member 42 consists of a tension spring member 100 secured at its lower end to a post 102 mounted on support bar 40 below lower yoke member 70 and attached at its upper end to a hook 104 on the outer surface of pressure plate 80 slightly above its connection with middle yoke member 90. This construction results in a normally open tapered opening 106 between pressure plate 80 and anvil member 42 with the upper end thereof having a width large enough to receive the end of a cigarette and the lower end thereof terminating in a gradually diminishing manner towards the lower end of pressure plate 80.

The upper end of pressure plate 80 may be equipped with an annular cigarette guide 110 located on the rear thereof in normal register with the cigarette opening 106 hereinabove discussed between pressure plate 80 and anvil member 42.

In the operation of the invention, a cigarette is inserted with its burning end into opening 106 between anvil member 42 and pressure plate 80 as illustrated in FIGURE 10. Finger pressure in a downward direction upon cross bar 66 of upper yoke member 60 results in the clockwise rotation of member 60 as seen in FIGS. 6, 8 and 9 and the displacement of pressure plate 80 toward anvil member 42 by virtue of the pivotal connections 41 and 98 and the action of member 90. It can be seen that pivot point 98 is located below pivot point 41 to accomplish this result. This initial advance of pressure plate 80 towards anvil member 42 causes a squeezing action to be exerted upon the ashes of the end of the cigarette. The ashes and embers caught by the initial interaction of pressure plate 80 and anvil member 42 are crushed therebetween. The cushioning effect afforded by the resilient layer 46 of spongelike material effectively prevents the crushed ashes from "freezing" or packing against either anvil member 42 or pressure plate 80 due to the resulting lessening of the compressive forces exerted upon the ash particles. The ends 50 of spring members 48 are biased rearwardly by plate 80 and further allow for a build up in the pressure exerted without causing damage to the parts during the squeezing stroke.

After face-to-face contact is made between pressure plate 80 and anvil member 42, pressure plate 80 is displaced upwardly in sliding contact with anvil member 42 by virtue of the linkage between it and yoke members 60, 70 and 90. As shown in FIGURE 9, this coaction results from the pivoting of the rear 64 of upper yoke member 60 in an upward direction which causes middle yoke member 90 to be displaced upwardly with pressure plate 80. Lower yoke member 70 during this phase of the extinguishing process serves to pivotally hold the lower end of the pressure plate in substantial parallel relation to

anvil member 42 as the plate is moved upwardly and thus prevent binding. The sliding relation thus obtained between pressure plate 80 and anvil member 42 constitutes a wiping action calculated to effectively clean the ashes from pressure plate 80 and anvil member 42 and at the same time choke off and cool any embers that may remain after the aforementioned squeezing action. It will be undersotod that the squeezing and the wiping actions referred to herein actually take place together when the upper yoke 60 is depressed in a single stroke. The cigarette is ejected from opening 106 during the extinguishing process.

Additional resilient stop means may be provided in the form of a resilient pad 120 of sponge rubber or similar material located along the rear face of support bar 40 beneath and engageable with the rear cross bar 74 of lower yoke member 70 during the wiping action hereinabove described. This permits of a more gradual transfer of pressure between plate 80 and anvil member 42 in addition to the cushioning effect afforded by resilient layer 46 contained within shell 44 of anvil member 42.

It will be seen that the ends 50 of the hook members 48 provide a stop or depth gauge for the end of the cigarette as it is inserted for snuffing. The ends 50 engage the end edge of the cigarette paper, and as a result, the cigarette is properly positioned for snuffing and ejecting.

While a preferred embodiment of the invention has been shown and described, it is to be understood that many substitutions and equivalents could be made without departing from the spirit and scope of the invention as defined by the appended claims.

I claim:

1. A cigarette extinguishing device having a substantially stationary anvil slightly inclined with respect to the vertical, an extinguishing plate adapted to be moved with respect to the anvil, and means for moving the extinguishing plate including a first arcuately movable member overlying said extinguishing plate and being adapted for pivotal rotation about a point intermediate the length of said first arcuately moveable member and about a first axis disposed adjacent the upper end of said anvil and through said intermediate point, first linkage means comprising a first arm, the first arm being pivotally secured at one end to said extinguishing plate and being pivotally secured at an intermediate point along the length thereof to said anvil, and second linkage means comprising a second arm, the second arm being pivotally secured at one end to said extinguishing plate at a point above said first linkage means, and being pivotally secured at its other end to said first arcuately moveable member at a point remote from said extinguishing plate, said arcuate member having a free end opposite said connection with said second arm, said free end being adapted to be pivoted and moved downwardly, the pivotal connection of said second arm with said first arcuately moveable member being disposed below the pivotal connection of said first arcuately moveable member with said anvil, whereby arcuately downward movement of the free end of said first arcuately moveable member moves said extinguishing plate toward said anvil.

2. The cigarette extinguishing device as described in claim 1 being particularly characterized in that a stop member is disposed along said anvil, the stop member being normally arranged to extend out of said anvil and toward said extinguishing plate, and being adapted to engage the end of a cigarette whereby to longitudinally position the same between said anvil and said extinguishing plate.

3. The structure as described in claim 2 being characterized in that said stop member is resilient and retractably mounted relative to the plane of said anvil, the stop means being normally biased toward said extinguishing plate and being adapted to be moved into a retracted position into the plane of said anvil.

4. The cigarette extinguishing device described in claim

1 wherein means are provided for mounting said device upon an ash tray having a raised circular rim and a recessed bottom, said mounting means including hinged means secured to the rim of said ash tray, said anvil being adapted to normally rest upon the recessed bottom of said ash tray when said device is in a position of rest upon said ash tray.

5. A cigarette extinguishing device having a substantially stationary anvil slightly inclined with respect to the vertical, an extinguishing plate having an anvil engaging surface and being adapted to be moved with respect to the anvil, and means for moving the extinguishing plate including a first arcuately moveable member overlying said extinguishing plate and being adapted for pivotal rotation about a point intermediate the length of said first arcuately moveable member and about a first axis disposed adjacent the upper end of said anvil and through said intermediate point, first linkage means comprising a first arm, the first arm being pivotally secured at one end to said extinguishing plate and being pivotally secured at an intermediate point along the length thereof to said anvil, the other end of said first arm being arranged to engage the lower end of said anvil upon pivotal rotation about said pivot point, and second linkage means comprising a second arm, the second arm being pivotally secured at one end to said extinguishing plate at a point

above said first linkage means, and being pivotally secured at its other end to said first arcuately moveable member at a point remote from said extinguishing plate, said arcuate member having a free end opposite said connection with said second arm, said free end being adapted to be pivoted and moved downwardly, the pivotal connection of said second arm with said first arcuately moveable member being disposed below the pivotal connection of said first arcuately moveable member with said anvil, whereby initial arcuately downward movement of the free end of said first arcuately moveable member moves said extinguishing plate arcuately toward said anvil until further movement thereof is limited by said anvil, and whereby continued downward movement of said member is adapted to move the extinguishing plate substantially parallel to the plane of said anvil.

10 6. The cigarette extinguishing device as described in claim 5 being particularly characterized in that said anvil is provided with resilient mounting means adapted to normally urge said anvil toward said extinguishing plate.
